(57) **CLAIM**

I claim the ornamental design for pants, as shown and described.

DESCRIPTION

FIG. 1 is a front elevation view of a pair of pants, according to the present design;

FIG. 2 is a left side elevation view thereof;

FIG. 3 is a rear elevation view thereof;

FIG. 4 is a right side elevation view thereof;

FIG. 5 is a front elevation view of the pants in an unzipped state; and,

FIG. 6 is a left side elevation view, the right side elevation view being a mirror image thereof.

The even-dash broken lines in the drawings represent stitching and environment forming no part of the claimed design.
